J. S. JOHNSTON

CARTRIDGE MAGAZINE FOR MACHINE GUNS

Filed Aug. 25, 1917

Patented Mar. 6, 1923.

1,447,860

UNITED STATES PATENT OFFICE.

JAMES S. JOHNSTON, OF UTICA, NEW YORK.

CARTRIDGE MAGAZINE FOR MACHINE GUNS.

Application filed August 25, 1917. Serial No. 183,084.

To all whom it may concern:

Be it known that I, JAMES S. JOHNSTON, a citizen of the United States, residing at Utica, in the county of Oneida and State of New York, have invented certain new and useful Improvements in Cartridge Magazines for Machine Guns, of which the following is a specification, reference being had therein to the accompanying drawing.

10 My invention relates to a cartridge magazine for machine guns and I declare the following to be a full, clear, concise and exact description thereof sufficient to enable any one skilled in the art to which it appertains to make and use the same reference being had to the accompanying drawings in which like reference characters refer to like parts throughout the specification.

The object of the invention is to provide 20 a magazine for machine guns that will utilize the empty shells for forcing or crowding the loaded shells into loading position. To this end, the magazine is constructed to receive the empty shells at one side of the 25 firearm and discharge the loaded cartridges into the cartridge carrier of the firearm at the opposite side. An expansive spring is employed to take up vacant space left unoccupied in the magazine after the first 30 three shells have left and before the first empty shell reaches the same.

The object will be understood by referring to the drawings in which:

Fig. 1 is a fragmentary view of the magazine, showing an elevation;

Fig. 2 is a fragmentary detail view, showing the first cartridge leaving the magazine and entering the carrier of the machine gun;

Fig. 3 is a fragmentary detail view, showing the second cartridge leaving the magazine and entering the carrier of the gun, the first cartridge having progressed to loading position;

Fig. 4 is a vertical section taken on the line 4-4 of Fig. 5 and looking in the direction of the arrows. This view shows the first cartridge progressed to third position, where it is about to enter the opposite end of the magazine;

Fig. 5 is a plan view of the magazine, showing parts broken away and in section;

Fig. 6 is a transverse section taken on the line 6-6 of Fig. 5;

Fig. 7 is a view looking into the end of the magazine, as indicated by the arrows on the line 7-7 of Fig. 5.

Fig. 8 is an enlarged fragmentary view, showing a section taken on the line 6-6 of Fig. 5.

Referring more particularly to the drawings, the magazine embodies a casing —1— forming a circuitous passageway for the travel of cartridges. The open space between the upper and lower passages will be covered by the casing —1—. The open ends 65 2 and 3 of the passageway permit of the admission and exit of the cartridges 4. The casing adjacent these open ends 2 and 3 has yielding projections 5—5 which slip over the shoulders 6—6 formed in the gun, when 70 the parts are assembled. The yielding projections 5 are made by slitting the surface of the casing —1—, as shown particularly by the dotted lines in Fig. 5. The slits terminate in the round holes adapted to add 75 to the yielding tendency of the free ends and the permanency thereof.

The casing —1— is held in assembled position upon the receiver portion of the gun 7 by a shoulder 8 thereon adapted to engage a correspondingly formed recess made by the shoulder 9 of the gun 7 and by the spring pressed latch 10 adapted to engage a correspondingly formed recess made by the shoulder 11 of the gun 7. The movement of the latch 10 is controlled by a finger piece 12 which is protected from jamming by the lugs 13—13 attached to the casing —1—. The finger piece 12 is held from moving completely away from the casing 90 —1— by a pin 15 working in an elongated slot 16 formed in the member 17 attached to the casing 1.

The casing —1— is provided with a peripheral indent 18, whereby to conform the 95 shape of the interior of the casing —1— to the smaller part of the cartridges 4 in order to keep said cartridges 4 from jamming. The lateral sides of the casing —1— are made with annular grooves 19—19 which 100 are intended to receive the correspondingly formed edges of the end plates 20—20 of the sectional spring 21, whereby to guide said spring in its course around the chamber. The annular grooves 19 terminate 105 just short of the open ends of the chamber, thereby leaving a shoulder to prevent the escape of the spring 21.

In operation, the chamber formed by the casing —1— will be filled with the cartridges 4 by pushing the same into the chamber at the open end 3 until said cham-

ber is filled and the sectional spring 21 compressed to the degree illustrated in Fig. 1. Thus filled, the casing will be mounted upon the gun 7 by inserting the shoulder 8 of the casing —1— into the recess formed by the shoulder 9 of the gun. The latch 10 will automatically engage the recess formed by the shoulder 11 and the yielding projections 5 will slip over the shoulders 6 of the gun. Immediately the casing —1— is assembled, the first cartridge 4 will drop into the carrier 20^a thereof, as shown in Fig. 2. The spring 21 will expand to just that degree permitted by reason of the removal of the first cartridge from the casing —1—. By working the bolt of the gun, a second cartridge 4 will drop into the carrier and the first cartridge 4 will move into loading position, leaving the spring to expand still further or the distance measured by the diameter of two cartridges, as shown in Fig. 3. After the gun is fired, the empty shell will be carried around into the location shown in Fig. 4 or adjacent the sectional spring 21, which has expanded now to a space measured by the diameter of three cartridges. Thereafter the empty shells which follow this first, will push the spring 21 around the chamber until the same is halted by the shoulders opposite the opening 3.

The casing —1— can be removed now by manipulating the finger piece 12 to release the latch 10 from the recess formed by the shoulder 11 on the gun 7. The empty shells are expelled and loaded cartridges substituted.

The sectional spring 21 may be made in separate parts, if desired, so as to facilitate the passage of the spring around the chamber of the casing —1—.

Having thus described my invention what I claim as new and desire to secure by Letters Patent is:

1. In a cartridge magazine for machine guns, a demountable casing, a circuitous passageway in said casing, means for permitting the empty shells to reenter said passageway, whereby to press the loaded shells into firing position and means lo-

cated in said casing for taking up any slack space in said passageway.

2. In a cartridge magazine for machine guns, a casing, a circuitous passageway in said casing, means for permitting the empty shells to reenter said passageway, whereby to press the loaded shells into firing position, and a sectional spring for taking up any slack space in said passageway.

3. In a cartridge magazine for machine guns, a casing, having a circuitous passageway, a spring pressed latch for detachably securing said casing to said machine gun, means for permitting the empty shells to reenter the passageway, whereby to push the loaded shells into firing position and means for taking up any slack space in said passageway.

4. In a cartridge magazine for machine guns, a casing, a circuitous passageway in said casing, a spring pressed latch for securing said casing to the machine gun, means for permitting the empty shells to reenter said passageway, whereby to push the loaded shells into firing position, and a sectional spring for taking up any slack space in said passageway.

5. In a cartridge magazine for machine guns, a casing, a circuitous passageway in said casing, a spring pressed latch for securing said casing to said machine gun, openings for permitting the empty shells to reenter said passageway, whereby to push the loaded shells into firing position, and a movable spring for taking up any slack space in said casing.

6. In a cartridge magazine for machine guns, a casing having a circuitous passageway, a spring pressed latch for securing said casing to the machine gun, a finger piece for actuating said latch, means for permitting the empty cartridge shells to reenter said casing, whereby to push the loaded shells into firing position and means for taking up any slack space in said passageway.

In testimony whereof I have affixed my signature.

JAMES S. JOHNSTON.
